2,606,867

GASEOUS PHASE PHOTOHALOGENATION
OF HYDROCARBONS

John A. Pianfetti, South Charleston, and Robert W. Timmerman, Charleston, W. Va., assignors to Food Machinery and Chemical Corporation, Wilmington, Del., a corporation of Delaware

Application September 16, 1948, Serial No. 49,622

15 Claims. (Cl. 204—163)

1

This invention relates to the production of halogenated hydrocarbons by the direct halogenation of hydrocarbons and of incompletely halogenated derivatives thereof.

Direct halogenation has heretofore been accomplished experimentally by three general methods, namely by thermal action, catalytic action and photochemical action. Commercialization of these processes has been prevented or hindered by reason of a number of operational difficulties. Thermal processes involve very high temperatures, explosive dangers and difficulties as to corrosion as well as to the avoidance of decomposition products or other undesired derivatives. Catalytic processes have the disadvantages of objectionably high temperatures, explosive dangers, inability to prevent, or complications in preventing, overheating of the catalyst in reactors operated at high enough capacity for commercial success, and finally the high expense of operation.

Photochemical chlorination processes, though capable of operating at lower and more easily controlled temperatures than the foregoing processes, have the disadvantages that if they are operated at a sufficiently high capacity to be of commercial interest, they not only involve temperature regulation difficulties but also produce reaction product gases containing free chlorine which chlorine decreases substantially the difficulty of recovering the chlorinated hydrocarbons in bodies of acceptable purity. In the chlorination of hydrocarbons such as methane for example, the photochlorination rate becomes extremely slow after about 90 to 95% of the chlorine has reacted. If the process were run at a rapid rate thereby leaving residual chlorine in the chlorination products, such loss of chlorine to the reaction would make the operation inefficient. If the free chlorine were recovered for reuse, the cost of such recovery would render the whole process economically unsatisfactory.

An object of the present invention is to provide processes for the direct halogenation of hydrocarbons which do not involve the above described disadvantages and which are capable of operating at high throughput rates while at the same time producing halogenated hydrocarbon reaction products substantially free of halogen. Another object is to provide a halogenation process wherein the temperatures are sufficiently low and the manner of handling the halogen and the hydrocarbons is such as will avoid excessive corrosion of equipment and as well will not involve explosive dangers. Still another object is

2

to utilize reactors and other equipment for such process which are simple in construction and easy to operate.

More generally, the ultimate object is to provide low cost processes for producing any of a large number of halogenated hydrocarbons involving efficient utilization of the raw materials and equipment employed. Among the limited objects is one to provide a process capable of operation in such manner as to produce larger percentages of specifically desired halogenated hydrocarbons, such for example, as higher percentages of carbon tetrachloride from methane.

Broadly considered, the processes of the present invention involve a combination of photochemical halogenation followed by catalytic halogenation, all in the vapor phase. The reaction of the halogen with the methane or other compound is only partially completed by the action of actinic light rays and the reaction product gases including the unchanged reactants leaving the photochemical reaction vessel or reactor are subsequently reacted with the aid of a catalyst. Although elevated temperatures are employed in both reactions, they are moderate and are sufficiently low to permit avoidance of local overheating and to avoid decomposition of the reaction products and excessive corrosion of the equipment. The final reaction product gases leaving the catalytic reaction vessel or reactor show substantially 100% conversion or consumption of the halogen. In view of this freedom from halogen, the gaseous reaction products may be condensed, collected and separated into their various constituents without difficulty.

In this process the combination of photochemical halogenation with catalytic halogenation makes it possible to operate the reactors at a high capacity throughput. Operation of photochemical halogenation at high capacity is possible because no attempt is made to bring about complete consumption of the halogen therein and large diameter reactors of very simple construction can be and are employed. High capacity operation of the catalytic halogenator is likewise possible in this combination for the reason that the amount of halogen in the gases flowing through the catalyst is comparatively low, thus restricting the amount of reaction and the amount of exothermic heat developed in the reactor. Furthermore, the high volume of reaction product gases produced in the photochemical halogenation and present along with the reactant gases in the catalytic halogenator serves to absorb most or substantially all of the excess

exothermic heat and to prevent any local over-heating. Finally, high capacity operation is possible because catalytic chlorinators of simple construction are used in which a porous bed of coarse catalyst is contained, permitting free flow of the gases.

In all operations of the process the major part of the halogenation is brought about in the photochemical reactor or reactors and a minor part occurs in the catalytic reactor. In chlorination reactors, most efficient results are generally obtained when only about ten to fifteen per cent of the initial chlorine is left for reaction in the catalytic chlorinator. The reaction of this amount of chlorine in the catalytic reactor does not generate enough heat to involve difficulties in maintaining the temperatures within desired limits even in reactors of simple construction or without cooling facilities. In the preferred operation of the process of the present invention, the reaction product gases from the photochemical chlorinator are present in such quantity as to absorb all excess exothermic heat developed in the catalytic chlorinator and no radiation through external walls or into internal cooling tubes is required. The exterior walls may even be insulated thereby to obtain more uniform regulation of the temperature in the reactor.

In accordance with an important feature of the invention, the throughput rate at which the process is operated is increased by recirculating a part of the reaction product gases through the photochemical chlorinator or chlorinators in which the major part of the chlorination reaction takes place. Before they are reintroduced, the withdrawn gases are cooled somewhat but preferably only to a temperature still sufficiently elevated to heat the reactant gases to the desired temperature for immediate rapid reaction in the photochemical reactor. The recycled gas accomplishes a very successful regulation of the temperature in the photochemical chlorinator or chlorinators by absorbing the excess exothermic heat. The ratio of the recycled gases introduced into the chlorinator to the reactant gases is adjusted such that the temperature rise produced by the heat of the reaction is not great enough to cause any decomposition of the chlorination products or great enough to cause excess deterioration of the apparatus. The recycling of the gases and their admixture with the reactant gases before the latter are exposed to the actinic light or before they are heated to a high temperature serves the additional function of avoiding the formation of an explosive mixture.

In the preferred operation of the present invention, a series of photochemical chlorinators is employed in combination with a catalytic chlorinator. The particular number to be employed in the series to obtain most efficient results depends upon the reactants, their ratio with respect to each other and the throughput capacity to be employed. In any case, this provision makes possible a greater throughput capacity than otherwise would be obtainable. In the treatment of chlorine with methane in the molecular ratio of 3.5, a plant of the commercial capacity contemplated calls for five chlorinators in series, which capacity or total amount of chlorination would require about twenty-five photochemical chlorinators if they were operated in parallel.

The process of the invention is of particular value for the halogenation of methane and other low boiling hydrocarbons and partly chlorinated hydrocarbons. It is applicable generally for the

treatment of the same compounds to which photochemical and catalytic halogenations have been considered applicable following procedures suggested in the prior art. Practically considered, the new process is especially suitable for halogenating hydrocarbons of five or less carbon atoms, but higher molecular weight hydrocarbons can also be reacted.

The process is applicable to the halogenation of both saturated and unsaturated hydrocarbons, including the paraffins, as for example methane, ethane and propane, the olefins, as for example ethylene and propylene, the aromatics, the naphthalenes and the acetylenes, as well as their derivatives. The process may also be employed for the accomplishment of dehydrohalogenation by which halogenated alkynes are obtained and for the accomplishment of mixed halogenation reactions as with chlorine and bromine. Finally, the halogenation of propane or propene may be carried out in such manner that fission of the carbon-carbon bond occurs at the same time, resulting in the formation of mixed halogenated hydrocarbons as chloromethanes, chloroethanes or chloroethylenes which, through exhaustive chlorination, may be made to form carbon tetrachloride and perchloroethylene.

The process of the invention contemplates reacting chlorine with methane in molar ratios as low as 1 to 1 and as high as 4 to 1. The particular ratio employed to a large extent determines the number of chlorine atoms introduced into the hydrocarbon molecules.

For the chlorination of methane the preferred temperature for the operation of the photochemical chlorinator is in the range of 100° to 300° C. Temperatures as low as 50° C. and as high as 445° C. can be employed, however, but with less advantage. Although some decomposition of the reaction products occurs at temperatures above said range, under some circumstances temperatures as high as 600° C. may be employed without excessive penalty.

In operation of the catalytic chlorinator the preferred temperature is from 200° to 400° C. At such temperatures the chlorinator can be operated at sufficiently high capacity without involving difficulty of temperature control in the catalytic bed. The catalytic reaction can be carried out at a temperature as low as 100° C., but the resulting rate of reaction is ordinarily too slow for practical purposes. The temperature in the catalytic reactor may be permitted to rise to as high as 500° but ordinarily control of the reaction at such temperature is too difficult, and undesired reaction products are obtained. With suitable catalysts and high space velocities, it is possible to employ temperatures as high as 600° C. without causing excessive decomposition.

The foregoing temperatures applicable to the chlorination of methane are also applicable in general to other hydrocarbons and to partially chlorinated hydrocarbons. In bromination reactions the temperatures required are generally substantially lower. In any case the lowest temperature employable with any specific operation of the process is that which brings about an acceptable rate of reaction, and the highest temperature permissible is in general that which is just below that at which undesired decomposition becomes excessive. However, other factors such as corrosion difficulties, may dictate the use of lower temperatures than the theoretically permissible maximums, in which case temperatures below about 300° C. may be required.

The process of the present invention may be advantageously carried out in the apparatus illustrated in the accompanying diagrammatic drawing wherein the first photochemical chlorinator and the catalytic chlorinator are shown in part in vertical section. With reference to the drawing, there are shown five photochemical halogenators or chlorinators 10a to 10e inclusive and one catalytic halogenator or chlorinator 11, all connected in series. The chlorinators are constructed of lead, nickel or other material resistant to the corrosive action of the substances present. Each of the photochemical chlorinators is provided with a lamp 12 having therein a mercury arc or other source of actinic light. The said lamps are mounted in glass-walled light wells 13. Each of the chlorinators 10 is also provided with a perforated annular conduit 14 for discharging a cooling liquid upon the exterior walls. In connection with the chlorinators 10a and 10b, the conduits 14 are optional and are not ordinarily required in view of the high efficiency of the recycled gases hereinafter described in removing excess exothermic heat and controlling the temperature in the vessels.

In operation the methane or other hydrocarbon or chlorinated hydrocarbon is introduced through the inlet conduit 15 into the conduit 16 leading to a gas pump 17 from which the methane flows through conduit 18 to the first chlorinator 10a. The chlorine or other halogen is introduced from a supply conduit 19 into the conduit 18. The mixture of gases in this conduit 18 flows into the chlorinator 10a beneath an optional perforated false bottom 21 which serves to distribute the gas mixture and to suppress any burning tendency that might occur before the reactants are fully diluted with the partially reacted gases in the reactor. The perforations are of small diameter and preferably of $\frac{1}{2}$ inch size. The reactant gases or either of them, in some instances, may alternatively be introduced at other points in the system as directly into the bottom of the reactor instead of into the conduits 16 and 18.

The reactants and reaction products pass upwardly through the photochemical chlorinator 10a and are there exposed to actinic light. They pass through the reactor at a rate which effects only partial reaction of the chlorine and the hydrocarbon. The reaction products and remaining reactants leave the reactor 10a through the conduits 22 connected with the single conduit 23 leading to the second photochemical chlorinator 10b. From this conduit 23 a portion of the effluent gases, and usually a major portion thereof, is withdrawn in conduit 24 for recycling leading to a gas cooler 25 (which may be a conventional heat exchanger) the outlet side of which is connected to the conduit 16 leading to the conduit 18, into which conduits the initial materials to be reacted are introduced. The recycle gases mixed with the chlorine and methane gases serve to heat the same to the temperature required for the initiation of the photochemical reaction in the reactor 10a.

In some operations it is preferable to cool the effluent gas leaving the reactor 10a before the same is introduced into the reactor 10b. In this case the valve in line 23 is closed thereby causing all of the effluent gas to flow through the conduit 24 and cooler 25. Then part of the effluent gases to be fed to the second chlorinator 10b is taken off from the conduit 16 in the conduit 26 which connects with the line 23 leading into the bottom of the second photochemical chlorinator 10b.

The reactor 10b may be identical in structure to the reactor 10a and it is also preferably provided with similar means for recycling and cooling part of the effluent gas. Instead of employing a dual recycling system, a single system may be used in which the effluent gases from the reactor 10b to be recycled are divided and part introduced into reactor 10a and a part into reactor 10b.

In the second reactor 10b an additional part of the chlorination is effected. The effluent gases still containing free chlorine and compounds to be chlorinated leaving the top of the second photo chlorinator, pass through the conduit 27 into the bottom of the third photochemical chlorinator 10c and thence through the fourth and fifth chlorinators 10d and 10e in the same manner as hereinbefore described.

In a typical operation, about 50% of the initial chlorine is reacted in the first, and about 20% in the second photochemical chlorinator. In the last three photochemical chlorinators an additional 20 to 25% of the chlorine is reacted leaving from 5 to 15% of chlorine for reaction in the catalytic chlorinator 11. In view of the limited amount of reaction to be effected in the last four chlorinators, recirculating and cooling circuits are not ordinarily required.

The effluent gases leaving the fifth and last photochemical chlorinator 10e in the conduit 28 flows to the top of the catalytic chlorinator 11 and thence through an insulated chamber 29 containing a suitable catalyst and out through the conduit 30. The catalytic chlorinator is provided with an optional circuit for recycling the effluent gases, that is a conduit 31 interrupted by a gas cooler 32 and a gas pump 33. The presence and utilization of this circuit permits the system, if desired, to be operated such that a larger proportion of the chlorine can be reacted in the catalytic chlorinator and less in the photochemical chlorinator or chlorinators. The effluent gases can be recycled in amounts to absorb the excess exothermic heat. In the runs carried out up to the present time, most efficient results have been obtained when the proportion of the chlorine left to react in the catalytic chlorinator has not been sufficient to require recycling of effluent gases to absorb exothermic heat.

In the operation of the invention absorptive materials such as active carbon and active charcoal are preferred. However, in its broadest aspects the present invention contemplates the use of other non-metal catalysts such as phosphorus trichloride and of metal catalysts such as copper and other metals which can combine with chlorine to form salts reducible by hydrocarbons to liberate hydrogen chloride. Since the rate of reaction in the catalytic reactor used in the present process is slow due to the low percentage of free chlorine in the gaseous mixture, the space velocity must be low or the path of travel through the catalyst must be adequately long. As is shown in the drawing, a straight flow catalytic chamber of substantial length as compared with its cross section, will operate satisfactorily.

In the catalytic chlorinator 11 the remaining chlorine gas reacts with the remaining hydrocarbon or other chlorinatable material thereby providing substantially chlorine-free effluent gases in the exit conduit 30 leading to suitable recovery equipment usually including condensers and a water absorber for hydrogen chloride.

If so desired, the complete reaction of the chlorine may be aided by the introduction of hydrogen or other readily chlorinatable material into the

conduit 28 through the conduit 34, leading to the catalytic chlorinator 11. Furthermore, the invention broadly contemplates completion of the halogenation in a series of catalytic or thermal halogenators as well as in a single such halogenator.

Example 1

Into a system containing a single photochemical chlorinator connected to a single catalytic chlorinator, both of the construction hereinbefore described but having no means for the recycling of gases, there was introduced chlorine and methane at the rates of 11 pounds (0.155 mole) of the former and 0.7 pound (0.044 mole) of the latter per hour, the same being directed into the bottom of the photochemical reactor. The temperature therein was maintained at approximately 305° C. maximum. In this chlorinator, the chlorine and methane reacted to provide chlorinated hydrocarbons leaving only 10 to 11% of free chlorine in the effluent gases. These gases were then passed directly into and through the catalytic reactor containing activated carbon in which a maximum temperature of about 453° C. was reached. The final reaction product gases from this unit contained no free chlorine and consisted principally of carbon tetrachloride (94% of the condensed liquids) together with smaller amounts of other chloro methanes, with hydrogen chloride and a small amount of methane which escaped reaction.

Example 2

Into a system similar to the foregoing but containing the recirculation conduits, the pumps and cooling equipment hereinbefore described, 75 pounds of chlorine and 4.4 pounds of methane were introduced per hour (3.8 mols of chlorine per mol of methane). For each volume of reactants introduced, seven volumes of reaction product gases recycled from the photochemical chlorinator were added. The combined gases entered the chlorinator at a temperature of 258° C. In this photochemical chlorinator 86% of the chlorine in the feed reacted with the methane. The effluent gases from the photochemical chlorinator were then fed to the catalytic chlorinator under the same conditions and with substantially the same results as disclosed above in Example 1.

Example 3

Into a system including two photochlorinators, 177 pounds (2.5 mols) of chlorine per hour and 10.5 pounds (0.66 mol) of methane per hour were fed into the first chlorinator. In this first chlorinator the temperature was maintained at 258° C. by recycling effluent gas to the extent of 17.7 mols per hour, the said gases during recycling having been passed through an external cooler wherein the temperature was reduced to 110° C. from which cooler the gas flowed back to the same chlorinator. In this first chlorinator the chlorine reacted at the rate of 135 pounds per hour representing 76% of the net chlorine fed.

The non-recycled effluent gas after being cooled to 66° C. was then introduced into the second chlorinator wherein the heat of reaction raised the temperature of the gas to 263° C. In this second chlorinator the chlorine reacted at the rate of 24.4 pounds per hour representing 14% of the chlorine originally fed into the system. This additional reaction led to a total chlorine conversion in the two chlorinators of 90%. The effluent gas mixture from the second chlorinator could be introduced into the catalytic chlorinator

to carry the chlorination to completion, by following the procedure of Example 1.

Example 4

5 In the chlorinating system in the accompanying drawing a preferred procedure suggested by various experimental runs involves introducing chlorine in a quantity of about 1200 pounds per hour with methane in the molar ratio of 3.5 of the former to 1 of the latter into the first photochemical chlorinator 10a together with four times their volume of reaction product recycle gases. The temperature in this reactor is maintained at about 300° C. A test of the effluent gases will show that about 50% of the chlorine has been converted. The effluent gases from this first reactor are then mixed with about an equal volume of reaction product recycle gases and passed through the second photochemical reactor 10b at substantially the same temperature and in such reactor the total chlorine conversion will reach about 70%. The effluent gases from the second chlorinator in passing through the third, fourth and fifth photochemical chlorinators 10c, 10d and 10e at temperatures also maintained at about 300° C. will lead to reaction product gases having about 9% of the original chlorine in a free state.

30 The effluent gases from the fifth photochemical chlorinator 10e when passed through the catalytic chlorinator under the conditions hereinbefore described will produce chlorinated methane composed principally of carbon tetrachloride in a condition substantially free of chlorine.

25 The present invention can be operated in photochemical and catalytic reactors and with cooling means other than those specifically illustrated in the drawing. Apparatus of different construction and other sources of actinic light may be used.

40 The recirculation of the reaction product gases is a step the usefulness of which is not restricted to the herein described combination photochemical-catalytic halogenation process, for it may be used to advantage in any direct halogenation procedure whether it be photochemical, catalytic or thermic or any combination of the same including photochemical chlorination followed by thermic chlorination and/or catalytic chlorination. This recirculation of the effluent gases without the separation of any of the constituents does not materially add to the complexity of the process, whereas the recirculation of any separated constituent of the reaction product gases disadvantageously complicates the operation.

55 It should be understood that the invention is not limited to the raw materials and conditions of reaction specifically disclosed herein but that it extends to all equivalents which will occur to those skilled in the art upon consideration of the claims appended hereto.

We claim:

60 1. In gaseous phase elevated temperature processes for the halogenation of hydrocarbons and their incompletely halogenated derivatives, the improvement which comprises passing the material to be halogenated and a halogen into a zone effecting reaction by photochemical catalysis solely wherein the major part of the halogen combines to form halogenated derivatives, and passing the effluent gases leaving said zone composed of unhalogenated material and halogen and the halogenated derivative through a zone containing a solid catalytic substance as the sole catalytic agent wherein combination of the re-

maining halogen occurs, thereby producing halogenated hydrocarbon effluent gases substantially free of halogen.

2. In a gaseous phase elevated temperature processes for the chlorination of hydrocarbons and their incompletely chlorinated derivatives, the improvement which comprises passing the material to be chlorinated and chlorine into a zone effecting reaction by photochemical catalysis solely at a rapid rate which leaves a minor amount of unreacted chlorine in the effluent gases containing unreacted material as well as the formed chlorinated derivative thereof, and passing the hot effluent gases through a zone containing a solid catalytic substance as the sole catalytic agent wherein combination of the remaining chlorine occurs, thereby producing chlorinated hydrocarbon effluent gases substantially free of chlorine.

3. A process for producing halogenated hydrocarbons from hydrocarbons and incompletely halogenated derivatives thereof which comprises mixing the compound to be halogenated with a halogen, reacting the mixture in a zone effecting reaction by photochemical catalysis solely in a continuously flowing gaseous stream of a rapidity which leaves a minor amount of unreacted halogen in the reaction product gases containing halogenated hydrocarbon and unreacted compounds, passing the reaction product gas mixture into a zone containing a solid catalytic substance as the sole catalytic agent, forming additional halogenated hydrocarbons in said zone by reactions involving the remaining halogen, thereby producing halogenated hydrocarbon effluent gases substantially free of halogen, and taking up excess exothermic heat developed in the catalyst by transfer to the reaction gases from both the photochemical and catalytic reactions whereby decomposition of the halogenated hydrocarbons obtained is avoided.

4. A process for producing chlorinated hydrocarbons from hydrocarbons and their incompletely chlorinated derivatives which comprises continuously passing a gaseous mixture of the compound to be chlorinated together with chlorine through a zone effecting reaction by photochemical catalysis solely at a rapid rate which produces chlorinated hydrocarbon reaction product gases containing not more than fifteen per cent of the original free chlorine, passing the effluent gases containing unchanged reactants through a zone containing a solid catalytic substance as the sole catalytic agent wherein combination of the remaining chlorine occurs thereby producing chlorinated hydrocarbon effluent gases substantially free of chlorine.

5. A process for producing chlorinated hydrocarbons from hydrocarbons and their incompletely chlorinated derivatives which comprises exposing a continuously flowing gaseous stream of the compound to be chlorinated together with chlorine into a zone effecting reaction by photochemical catalysis solely thereby reacting the gases at a temperature of from about 100° C. to about 300° C., regulating the rate of flow at a rapidity which leaves in the effluent gases a small amount of chlorine not in excess of 15% of the original amount, passing the effluent gases containing unchanged reactants through a zone containing a solid catalytic substance as the sole catalytic agent wherein combination of the remaining chlorine occurs thereby producing chlorinated hydrocarbon effluent gases substantially free of chlorine.

6. A process for producing chlorinated hydrocarbons from hydrocarbons and their incompletely chlorinated derivatives which comprises, continuously passing a gaseous mixture of the compound to be chlorinated and chlorine together with recycle gases hereinafter defined, through a zone effecting reaction by photochemical catalysis solely at a rapid rate which produces chlorinated hydrocarbon reaction product gases containing a minor amount of the initial chlorine, dividing the said reaction product gases into two parts, cooling one part of said gases and recycling the same into the said photochemical reaction zone as hereinbefore described, the said part recycled through the said zone being in an amount which takes up excess heat and prevents decomposition of chlorinated hydrocarbons in the said zone, passing the remaining part of the reaction product gases containing unchanged reactants through a zone containing a solid catalytic substance as the sole catalytic agent wherein combination of the remaining chlorine occurs, thereby producing chlorinated hydrocarbon effluent gases substantially free of chlorine.

7. A gaseous phase, elevated temperature process for the halogenation of hydrocarbons and their incompletely halogenated derivatives, which comprises passing the compound to be halogenated and the halogen first through a zone effecting reaction by photochemical catalysis solely wherein the major part of the halogen is reacted, passing the reaction product gases containing the remaining reactants through a zone containing a solid catalytic substance as the sole catalytic agent to accomplish completion of the reaction of the halogen whereby halogenated hydrocarbon effluent gases substantially free of halogen are obtained, controlling the temperature in the photochemical reaction zone by recirculating part of the undivided reaction product gaseous mixture and cooling the same before said part is introduced into the photochemical reaction zone together with the reactants.

8. In a gaseous phase, elevated temperature process for the halogenation of hydrocarbons and their incompletely halogenated derivatives, the improvement which comprises passing the material to be halogenated and a halogen into and through a series of zones effecting reaction by photochemical catalysis solely at a rapid rate which leaves a minor amount of unreacted halogen in the effluent gases of the last reaction zone, passing the effluent gases containing the unreacted material together with the halogenated hydrocarbons formed through a zone containing a solid catalytic substance as the sole catalytic agent wherein a combination of the remaining halogen occurs, thereby producing halogenated hydrocarbon effluent gases substantially free of halogen.

9. A process for producing chloromethanes from methane which comprises continuously passing a gaseous mixture of methane and chlorine successively through a series of zones effecting reaction by photochemical catalysis solely at a rapid rate which produces chloromethane effluent gases containing not more than 15% of the original free chlorine, passing the effluent gases containing unchanged reactants together with chloromethanes through a catalytic reaction zone containing a solid catalytic substance wherein as the sole catalytic agent combination of the remaining chlorine occurs, thereby pro-

ducing chloromethanes in a condition substantially free of chlorine.

10. A process for producing chlorinated hydrocarbons from hydrocarbons and their incompletely chlorinated derivatives which comprises continuously passing a gaseous mixture of the material to be chlorinated and chlorine together with recycle gases hereinafter defined through a series of zones effecting reaction by photochemical catalysis solely at a rapid rate which produces chlorinated hydrocarbon reaction product gases containing not more than 15% of the initial chlorine in a free state, dividing the said reaction product gases leaving the first zone of said series into two streams, cooling one stream of said gases and recycling the same into said first zone as hereinbefore described, then passing the second stream of the reaction product gases after leaving the last zone of said series through a catalytic reaction zone containing a solid catalytic substance as the sole catalytic agent wherein combination of the remaining chlorine occurs, thereby producing chlorinated hydrocarbon effluent gases substantially free of chlorine.

11. A process for producing chloromethanes from methane which comprises continuously passing methane and chlorine together with recycle gases hereinafter defined through a series of five zones effecting reaction by photochemical catalysis solely at a rapid rate which produces chloromethanes containing a minor amount of the initial chlorine, dividing the effluent gases leaving the first zone of the series into two streams, cooling one stream of said gases and recycling the same into the said first zone as hereinbefore described, passing the remaining stream of effluent gases containing chloromethane gases, unchanged methane and chlorine after they leave the fifth zone of said series through a zone containing a solid catalytic substance as the sole catalytic agent wherein combination of the remaining chlorine occurs, thereby producing chloromethanes in a condition substantially free of chlorine.

12. A process for the chlorination of hydrocarbons having up to five carbon atoms and their incompletely chlorinated derivatives which comprises, passing vapors of the material to be chlorinated and chlorine into a zone effecting reaction by photochemical catalysis solely at a rapid rate which produces chlorinated hydrocarbon reaction product gases containing part of the original free chlorine but not more than 15% thereof, passing the effluent gases containing unchanged reactants through a reaction zone containing a solid catalytic substance, as the sole catalytic agent wherein combination of the remaining chlorine occurs, thereby producing chlorinated hydrocarbon effluent gases substantially free of chlorine.

13. A process for the halogenation of hydrocarbons having up to three carbon atoms and their incompletely halogenated derivatives in the gaseous phase at elevated temperatures which comprises, passing vapors of the material to be halogenated and a halogen into a zone effecting reaction by photochemical catalysis solely wherein a larger part of the halogen is combined to form halogenated derivatives, and passing the

effluent gases containing not more than 15% of the original free halogen through a reaction zone containing a solid catalytic substance as the sole catalytic agent wherein combination of the remaining halogen occurs, thereby producing effluent gases substantially free of halogen containing the halogenated hydrocarbon of not more than three carbon atoms.

14. A process for the chlorination of hydrocarbons having up to three carbon atoms and their incompletely chlorinated derivatives in the gaseous phase at elevated temperatures which comprises, passing the material to be chlorinated and chlorine into and through a series of zones effecting reaction by photochemical catalysis solely at a rapid rate which leaves a minor amount of unreacted chlorine in the effluent gases of the last reaction zone, passing the effluent gases containing unreacted hydrocarbon material and the remaining chlorine together with the chlorinated hydrocarbons formed through a reaction zone containing a solid catalytic substance as the sole catalytic agent wherein combination of the remaining chlorine occurs, thereby producing effluent gases substantially free of halogen composed of chlorinated hydrocarbons having up to three carbon atoms.

15. A process for producing chlorinated hydrocarbons from hydrocarbons having up to three carbon atoms and their incompletely chlorinated derivatives in the vapor phase at elevated temperatures which comprises, continuously passing a gaseous mixture of the material to be chlorinated and chlorine together with recycle gases hereinafter defined through a series of zones effecting reaction by photochemical catalysis solely which produces in the effluent gases of the last of the reaction zones chlorinated hydrocarbon reaction product gases containing part of the initial chlorine in a free state but not more than 15% of the original amount, dividing the effluent reaction product gases of the first zone of the series into two streams, cooling one stream of said gases and recycling the same into said first zone as hereinbefore described, then passing the second stream of the reaction product gases of said effluent gases through a zone containing a solid catalytic substance as the sole catalytic agent wherein combination of the remaining chlorine occurs, thereby producing effluent gases substantially free of chlorine composed of chlorinated hydrocarbons having up to three carbon atoms.
